ARTIFICIAL BODY MEMBER

Filed July 17, 1931

Inventor:
Arthur H. Owen,
Raymond Jones.
Att'y.

UNITED STATES PATENT OFFICE

ARTHUR H. OWEN, OF MOBERLY, MISSOURI

ARTIFICIAL BODY MEMBER

Application filed July 17, 1931. Serial No. 551,512.

My invention relates to artificial body members and has particular reference to an artificial hand portion which comprises mainly a series of finger elements.

5 The hand portion constructed according to my invention is particularly adapted to be secured to the hand of a person to replace a hand extremity that has been severed along a line transversely through the metacarpal 10 bones and adjacent the outer ends thereof.

I provide, in my novel combination, an artificial thumb portion adapted to replace a thumb portion which has been severed at a point between the two joints thereof.

15 The main object of my invention is to provide an artificial hand portion comprising a rigid finger portion having means for attachment to the hand of the user.

Another object is to provide an artificial 20 thumb portion having means for attachment to a thumb stub including means for attachment to the main finger portion.

Another object is to provide a novel socket member in an artificial hand portion having 25 adjustable means for firmly securing the portion of the wrist of a user.

Another object is to provide a hand member having a maximum of strength and a minimum of weight.

30 A further object is to provide a hand member that has the elements thereof so shaped and arranged as to afford to the user the ability to perform many acts and tasks usually done by means of a normal hand.

35 Other objects will appear from the detailed description which follows when considered with the accompanying drawing, wherein—

Figure 1 shows a front or palm view;

Fig. 2 shows a rear view;

40 Fig. 3 is a side view, partly cut away to show details; and

Fig. 4 is a view in cross-section of my improved artificial member.

Referring to the drawing in detail, the 45 hand member comprises three main elements, a finger portion 1, a thumb portion 2 and a palm socket member 3. The finger portion 1 is formed as an aluminum casting to reduce weight and the four finger members are 50 rigidly connected to a short base portion 4

which is hollowed out as at 5 to provide a socket which terminates in reduced edge portions 6. The fingers may be made hollow, as shown by dotted lines, near their enlarged inner ends to reduce weight. One side of the 55 casting is extended inwardly as at 7 for a purpose to be described. Each finger member is formed with a permanent bend to facilitate use of the hand.

The palm socket member 3 is formed preferably of leather and is attached to the portion 1 by means of a series of rivets 8 which are passed through the reduced edge portions 6. The inner, open, free end of the socket 3 is reduced in width and is provided with a 60 wrist strap 9 which is sewed at one end to the socket member and which is adapted to adjustably engage a buckle 10 attached to the opposite side of the socket 3. A leather tab 11 is sewed to the edge of the socket 3 in position to underlie the strap 9 to prevent cutting of the wrist of the user by the strap 9.

65 A tension brace or strap 12 is riveted at 13 to the portion 1 and adjustably engages a buckle 14 which is attached to a short tab 15 70 sewed to the inner or wrist edge of the socket member 3. By taking up the strap 12, the finger portion 1 may be pulled tightly inwardly towards the wrist strap 9 and any undue strain or pull outwardly on the bent finger 75 elements is transmitted directly to the wrist strap 9.

80 A soft fibre padding or stuffing 16 is provided in the hollow 5 and a soft lining 17 of chamois or the like is arranged on the inner 85 surface of the leather socket portion 3 and attached thereto by stitches along the edge of the socket.

85 The thumb member 2 is attached to the tab 11 preferably by means of an electric strap 90 18. The thumb member 2 comprises an outer portion 19 formed from cork or similar light material. The portion 19 is attached to a socket 20 formed from leather which, in turn, is attached to an end of the strap 18. The 95 elastic strap or tape 18 is effective to yieldably retain the thumb member in place upon the stub thumb of the user and, at the same time, allow for movement of the member relative to the finger portion 1.

- In the operation and use of my device, the stub end of the hand of the user is inserted within the socket member 3 and the stub thumb is inserted within the thumb socket 20. 5 The strap 9 is then buckled and pulled tightly around the wrist of the user. The curved or hook shaped finger elements are adapted to engage objects to be handled and any load or strain applied to the finger elements is transmitted directly to a point adjacent the wrist of the user. The thumb portion 2 is effective to engage objects and hold them against the finger elements. It has been found that a pencil or pen may be retained 10 in this manner and manipulated in writing with facility. 15
- While I have shown and described a preferred form of my invention for the purpose of its illustration, modifications thereof are contemplated such as may fall within the scope of the claims which follow. 20
- What I claim is:
1. An artificial hand comprising a base portion having integral finger elements, a flexible palm portion shaped to receive the stub palm of a user, said palm portion being connected to the base portion to form an extension thereof, an adjustable tension member, said member being connected at one end 25 to said base portion and at its opposite end to said palm portion. 30
  2. An artificial hand comprising integral- 35 ly connected finger elements, a socket member connected to said finger elements and adapted to receive the stub palm of a user, an adjustable strap connected to the free end of said socket member for securing said member to the wrist of a user, a flexible and adjustable tension member, said member being connect- 40 ed to the finger elements at one end and at its opposite end to the socket member adjacent said adjustable strap. 45
  3. An artificial hand comprising a base portion having integral finger elements, a flexible palm portion shaped to receive the stub palm of a user, said palm portion being connected to the base portion to form an extension thereof, an adjustable tension member, said member being connected at one end 50 to said base portion and at its opposite end adjacent to the free end of said palm portion, a thumb member and means for yield- 55 ably connecting said thumb member to said palm portion. 60
  4. An artificial hand comprising a base portion having integral finger elements, a flexible palm portion shaped to receive the stub palm of a user, said palm portion being connected to the base portion to form an extension thereof, an adjustable tension member, said member being connected at one end 65 to said base portion and at its opposite end adjacent to the free end of said palm portion, a thumb member and elastic means for 70
